WRINGER

Wilmer A. Fulkerson, Brookfield, Mo.

Application April 14, 1936, Serial No. 74,329

2 Claims. (Cl. 68—264)

This invention relates to clothes wringers and has for its purpose to provide means for preventing damage to operators' hands and to articles of clothing passed therethrough.

5 It is an object of this invention to provide in such a wringer a multiple roll construction adapted to prevent the winding of the work on the squeeze rolls.

10 It is a further object of this invention to provide a hand guard in order to prevent the accidental engagement of the fingers of an operator with the squeeze rolls of the wringer.

15 It is a further object of this invention to provide stripper means for preventing articles of clothing winding on the squeeze rolls of the wringer.

It is a further object of this invention to provide a self-feed for a wringer.

20 It is a further object of this invention to provide a drain board having a splash board adjustably secured thereto, whereby to prevent drainage to the delivery side of the wringer and contact with the wrung or dried work.

25 It is a further object of this invention to provide such a drain board which is rigidly attached to the wringer frame and may serve to operate in the above manner to drain selectively to either side of the drain board to provide for reversible operation of the wringer without the use of an adjustably mounted drain board.

30 These and other advantages will appear from the following description taken in connection with the drawings.

35 In the drawings:

Figure 1 is a front elevational view of the wringer, with the frame latch in open position;

Figure 2 is an end elevational view of the wringer, as seen from the left end of Figure 1, with the roller drive cover removed to show all

40 the roll drive means;

Figure 3 is an elevational view in section of the wringer, taken on the line 3—3 of Figure 1;

Figure 4 is a plan view of the drain board and attached splash board; and

45 Figure 5 is an elevational view in section, taken along the line 5—5 of Figure 4.

Referring to the drawings in detail, the frame comprises a longitudinal member 1 having side frame standards 2 rigidly attached, at their lower ends, thereto. Adapted to be secured to the upper ends of the side standards 2 is a top member 3, which has therein at one end a depression 4 adapted to engage a complementary projection of one of the side standards 2, while 55 a latch member 5 is pivotally mounted at the

opposite end of the top member and is adapted to be selectively engaged with or disengaged from a projection 6 on the opposite side standard. The side standards 2 are each shaped substantially like an inverted cross having a horizontal portion 7 extending in both directions adjacent the base of the frame. The above described members are preferably of angle form and the members 2 each have inwardly directed substantially U-shaped flanges which extend at either side of the squeeze rolls and around and adjacent the lower portion of the lower squeeze roll. The horizontal portion 7 serves to support bearing members 9, in which are journaled the ends of the lower rolls of the wringer. These bearing members, as shown, are of wood, but it is understood that any other suitable material may be used and that the construction of these bearings may be varied within rather wide limits. The lower rolls are three in number and comprise 20 a centrally located lower squeeze roll, generally designated 10, and guide and stripper rolls 11 disposed at either side thereof and having light contact therewith. The rolls 10 and 11 comprise 25 pintles rigidly secured to nonresilient bodies, which bodies have resilient clothing or covers of rubber or equivalent resilient material.

The pintle of the roll 10 extends beyond one end of the roll 10 a substantial distance and terminates in the shaft portion 12 having a key-way 13 to provide means for attaching to the shaft portion 12 suitable power means, such as a drive pulley, gear or hand crank. Suitable bearing means 14 is slidably supported by the upper vertical portions of the side standards 2 and 30 the upper squeeze roll 15, which is of construction similar to rolls 10 and 11, is journaled at each end to be freely rotatable therein. The bearing members 14 are urged downwardly by a leaf spring 15a which has each end resting upon 35 one of the bearing members 14 and has a depression 16 in a central portion, in which is adapted to rest the lower end of an adjusting screw 16. By this means, the pressure of contact between 40 the upper squeeze roll 15 and the lower squeeze 45 roll 10 may be adjusted as desired.

Suitable attaching means, such as bolts 17 and wing nuts 18, are provided for attachment of the lower frame member 1. The upper squeeze roll 15 is freely rotatable and resiliently urged 50 downwardly against the lower squeeze roll 10, as pointed out above. The guide and stripper rolls 11 and lower squeeze roll 10 are all driven at the same speed and in the same direction. The means for accomplishing the joint drive of 55

these rolls comprises the gear 19, non-rotatably secured to the pintle of the roll 10, adjacent one side standard, the gears 20 attached in like manner to the pintles of the rolls 11 and the idler gears 21, which drivingly connect the gear 19 with each of the gears 20, and which idler gears are mounted for free rotation on pintles 22, which are secured to the plate 23. The plate 23 is rigidly secured to one of the side standards and 10 is adapted to have a housing or gear casing 24 suitably attached thereto by means of screws or studs 25. The bolts 17 and nuts 18 also provide means for attaching the drain board 26 to the upper surface of the frame member 1, as 15 is shown particularly in Figure 3. The drain board is substantially rectangular, but has the side edges thereof arcuate, as shown particularly in Figure 4. The upper surface of the drain board inclines downwardly from the center at a slight 20 angle, as may be clearly seen in Figures 3 and 5. The heads of the bolts 17 are adapted to be attached to the drain board 26 through the circular portion of the keyhole slot 21. The arcuate side flanges of the drain board are designated 25 28 and have pivotally secured thereto by means of rivets 29 or other suitable pintle means, side flanges 31 of splash board 30. The upper surface of the splash board 30 is arcuate and concave, as is shown particularly in Figures 3 and 5.

30 Suitably attached at each side of the vertical portion of each side standard 2 is a lug 32, which has a hole therein, which is adapted to receive the upper hook portion 34 of a stripper plate supporting arm 33. The arms 33 are thus removable and pivotally attached to the wringer frame. A stripper support member 35 of angle form is secured at either end to one of the paired stripper plate supporting arms 33 at each side of the wringer frame. Rigidly secured to the stripper 40 support member by means of plate 37 and a plurality of screws 38 is a resilient stripper plate 36 of rubber or other equivalent resilient material. Rotatably supported below the stripper and between the stripper plate support arms 33 by 45 means 39 is a guard roller 40. As shown, this means 39 comprises a pair of screws which rotatably support the ends of the roller 40, but it is to be understood that a rod extending between the arms 33 and secured at each end to one of 50 said arms, may be used. The guard rollers 40, as illustrated, are metallic, but it is to be understood that the showing thereof is merely illustrative and that the construction thereof may be varied within rather wide limits.

55 Operation

With reference particularly to Figure 3 of the drawings, it will be seen that, upon application of power to rotate the roll 10 in a clockwise direction, the rolls 11 will also be rotated at the same speed and in the same direction, while the upper squeeze roll 15 will be rotated in a counterclockwise direction by contact with roll 10. The operator applies pressure to the left side of 65 the splash board 30 and tilts it until the lefthand edge thereof is in contact with the top surface of the drain board 26. Clothing is then inserted between the lefthand guard roller 40 and the left-hand roll 11 which is, in this case, the feed roll. 70 Contact of the operator's hand with the guard roller 40 will prevent the hand from being caught between rolls 10 and 15. This is facilitated by the rotatable mounting of the roller 40. The contact of the operator's hand with the roller 40 75 will swing stripper plate supporting arms 33

toward the roll 15 and the stripper plate 36 will be brought into contact with the roll 15. The contact of the stripper plate 36 with the roll 15 will prevent clothing from being wound on the roll 15 during operation of the wringer.

The clothing is carried by the feed roll 11 into contact with the lower squeeze roll 10, which is driven, and thence between the lower squeeze roll 10 and the upper squeeze roll 15. When the clothing travels to the right of the squeeze rolls, 10 there will be a tendency to travel around the periphery of the lower squeeze roll 10, but this is prevented by the driven rotation of the right-hand roll 11 which, in this case, is the stripper roll and tends to strip the work from the lower 15 squeeze roll 10 and prevent it from being wrapped around the lower squeeze roll and thus preventing injury thereto.

When the splash plate 30 is tilted in the above-described position, its righthand edge is adjacent the lower peripheral portion of the stripper roll 11, and it is thus seen that liquid removed from the work is transferred by the splash plate 30 to the lefthand inclined surface of the drain board 26 and prevented from reaching the righthand portion of the drain board 26. It is, of course, to be understood that I comprehend the use of reversible drive means for driving the shaft portion 12 whereby to rotate the lower squeeze roll 10 in either direction. When the direction of rotation is opposite that described above, the rolls 10 and 11 will rotate in a counterclockwise direction and the righthand roll 11 becomes the feed roll and the lefthand roll 11 becomes the stripper roll, and the upper squeeze roll 15 rotates in a clockwise direction and, instead of the splash board or plate 30 being tilted to the left, it will be tilted to its rightmost position and the righthand guard roller 40 and the righthand stripper plate 36 will operate in the same manner as the lefthand guard roller and lefthand stripper plate 36, described above. This is extremely convenient because the operator in reversing the operation of the wringer is not required to move anything but the splash board 30 which may be easily swung downwardly by a simple push, and it will be seen from Figure 4 that, when the lower rolls are rotating in a clockwise direction, the downward push is opposed by the guide roll 11 when the operator's hand comes 50 in contact therewith, whereby there is no possibility whatsoever that the operator's hand may be injured in performing this simple pushing operation. This structure thus makes the reversal of the operation of the wringer substantially instantaneous with the reversal of the power and greatly facilitates such operation of the wringer, while providing the utmost safety of operation.

It is thus seen that my invention consists of four features, namely, stripper plates 36, guard 60 rollers 40, driven feed roll, driven stripper roll and rigidly mounted drain board 26 having the splash board 30 adjustably mounted thereon, and it is, of course, to be understood that the omission of one will not affect the operation of the others. For instance, the guard roller 40 might be omitted, the stripper plate 36 might be omitted and one of the driven rolls 11 might be omitted with corresponding loss of function, where it was not desired to operate the wringer reversibly, 70 likewise the rigid drain board and adjustable splash board construction might be applied to wringers of substantially different construction and mode of operation from that described.

The above-described construction of the 75

wringer frame is merely illustrative and it is to be understood that my invention may be carried out with frames of widely varying constructions and that I do not intend to limit myself in any 5 way by the above description of one frame construction by which my invention may be carried out.

It will be further understood that the above-described structure is merely illustrative of one 10 manner in which my invention may be carried out and that I desire to comprehend within my invention such modifications as come within the scope of the claims and the invention.

Having thus fully described my invention, what 15 I claim as new and desire to secure by Letters Patent is:

1. In a wringer with a frame having mounted therein a lower driven squeeze roll and a freely rotatable upper squeeze roll resiliently urged 20 thereagainst, a pair of arms swingably mounted at one side of said frame and having a resilient

stripper plate secured thereto and adapted to be swung into contact with said upper squeeze roll to remove clothing therefrom, said arms having hand guard means attached to their lower ends adjacent said stripper plate.

2. In a wringer with a frame having mounted therein a driven squeeze roll and a freely rotatable squeeze roll resiliently urged thereagainst, a feed and guide roll mounted adjacent said driven squeeze roll and drivingly connected thereto to rotate in the same direction, a freely rotatable guard roller mounted on said frame for limited swinging movement toward said squeeze rolls to a point substantially centrally above said guide roll whereby to cooperate with said guide roll to prevent entry of the hand of an operator between said squeeze rolls, said guide roll rotating in such direction that portions thereof adjacent said guard roller travel away from the operator.
